UNITED STATES PATENT OFFICE.

ARTHUR EUGENE HALL, OF SYRACUSE, NEW YORK, ASSIGNOR TO ELLEN E. HALL, OF SYRACUSE, NEW YORK.

MACHINE FOR REMOVING THE SKINS FROM PEANUTS AND THE LIKE.

Application filed November 8, 1921. Serial No. 513,775.

To all whom it may concern:

Be it known that I, ARTHUR EUGENE HALL, a citizen of the United States, and a resident of Syracuse, in the county of Onondaga and State of New York, have invented a certain new and useful Machine for Removing the Skins from Peanuts and the like, of which the following is a specification.

This invention has for its object a machine for removing the skins from peanuts and for similar purposes, which machine is particularly simple in construction, and highly efficient, durable and rapid in use.

The invention consists in the novel features and in the combinations and constructions hereinafter set forth and claimed.

In describing this invention, reference is had to the accompanying drawings in which like characters designate corresponding parts in all the views.

Figure 1 is a fragmentary side elevation of a machine embodying my invention.

Figure 2 is a plan view of parts seen in Fig. 1.

Figure 3 is an elevation of another form of my invention, parts being removed.

Figure 4 is a sectional view taken centrally of Fig. 3.

This machine comprises generally, a passage for the peanuts or other articles to be operated on, the passage being open at one side, a brush or wiper carrier having brushes arranged to wipe along or over such open side, the brushes being usually sponge rubber.

The carrier is preferably a disk and the brush is carried on the side face of the disk and the disk arranged flatwise against the open side of the passage.

In Figs. 1 and 2, 1 designates the passage which is shown as arranged in vertical position and as having a hopper 2 at its upper end for receiving the peanuts, the passage 1 having two sides as its opposite sides open. 3 and 4 are the brush carriers suitably mounted so that their margins move on opposite sides of the passage 1 and along the open sides, that is, the margins of the carriers lap each other and the passage 1 extends between the lapping margins. Said carriers are mounted on axes extending transversely of the passage 1 and on opposite sides thereof and the axes are arranged at a right angle to the planes of the open sides. 5 designates the brushes or wipers carried

on the side faces of the carriers 3, 4; these 55 brushes being preferably sponge rubber.

The carriers 3, 4 are mounted upon suitable axles 6, 7 carried in suitable supports, not shown, and having pulleys 8 and 9 for connection to any source of power. 60 These carriers rotate in opposite directions so that their lapping margins move in the same direction as vertically, and one rotates at a greater rate of speed than the other. Owing to the fact that the margins of 65 the wipers travel in arcs and to the fact that the passage 1 is straight, the nuts are given a wiping movement transversely and longitudinally and also a rolling movement, all of which movements effect the complete 70 removal of the skins.

The peanuts may be fed into the hopper in any suitable manner, and as here shown, they are fed by a suitable conveyor constructed to arrange the peanuts end to end 75 so that they drop endwise through the passage 1. This conveyor is here shown as a belt 10 running over double conical pulleys, that is, pulleys having V-shaped peripheries so that the belts also take a V-shape in cross 80 section. The peanuts with the shells removed feed from the hopper 13, and are arranged in alignment in the V groove of the belt and are fed one by one into the passage 1. 85

In Figs. 3 and 4, a passage 14 open at one side, is shown, this passage extending across the side face of the rotatable brush carrier 15, and extending around the hub 16 of the carrier 15. This passage 14 is open at one 90 side only and the carrier 15 which is provided with brushes 16 on its side face is arranged so that the brushes wipe along the open side of the passage.

Owing to the arrangement of the passage, 95 the brushes on the upper side of the carrier move transversely in one direction across the upper end of the passage 14, then lengthwise of the passage around the central part thereof extending around the hub 17 and 100 then again transversely in the opposite direction around the portion of the passage opposite the lower side of the carrier 15. This complex action of the brushes removes all of the skins as they tend to turn or ro- 105 late the nuts in the passage.

What I claim is:

1. In a machine for removing the skins

from peanuts, comprising means for providing a passage for the nuts, the passage being open along one side, and rubbing means engaging the nuts in the passage through the 5 open side at a plurality of points, the means providing the passage being arranged, so that, the passage is vertical and open along the vertical side, whereby, the nuts feed through the passage by gravity, and the rubbing means being arranged to move in transverse directions across the passage at a plurality of points.

2. A machine for removing the skins from peanuts comprising means providing a passage for the nuts having openings on opposite sides thereof, and carriers having rubbing means movable along the opposite open sides of the passage, one of said carriers being movable at a different rate of speed than 15 the other, substantially as and for the purpose described.

3. A machine for removing skins from peanuts comprising means providing a passage open at opposite sides thereof, rotatable 20 carriers mounted on axes extending transversely of the passages, said carriers having their margins movable on opposite sides of the passage and provided with rubbing instruments movable along the open sides of

the passage, substantially as and for the purpose specified. 30

4. A machine for removing skins from peanuts comprising means providing a passage open on opposite sides thereof, rotatable carriers mounted on axes extending 35 transversely of the passages, said carriers having their margins movable on opposite sides of the passage and provided with a rubbing instrument movable along the open opposite sides, one of said carriers being movable at a different rate of speed than the other, substantially as and for the purpose described. 40

5. A machine for removing skins from peanuts comprising a passage open on opposite sides thereof, and rotatable carriers mounted on opposite sides of the passages on axes extending transversely of the passage, the carriers having their margins movable along opposite sides of the passage and provided with a rubbing instrument wiping along the open opposite sides, substantially as and for the purpose specified. 45 50

In testimony whereof I have hereunto signed my name at Syracuse, in the county of Onondaga, and State of New York, this 31st day of October, 1921. 55

ARTHUR EUGENE HALL.
